ARMREST FOR A CHAIR

Raymond T. Carlson, 1405 Peter Pan Road,
Lookout Mountain, Ga. 37350

Filed Sept. 29, 1969, Ser. No. 19,335

Term of patent 7 years

Int. Cl. D6—01

U.S. Cl. D15—1

The figure is a view in side elevation of an armrest for a chair showing my design.

The side not shown is a mirror image of the side shown.

I claim:

The ornamental design for an armrest for a chair, substantially as shown and described.
